UNITED STATES PATENT OFFICE

PHILIP E. MATTHEWS, OF PLAINFIELD, NEW JERSEY, ASSIGNOR TO INTERNATIONAL MOTOR COMPANY, OF NEW YORK, N. Y., A CORPORATION OF DELAWARE

DESIGN FOR A BUS

Application filed April 17, 1931. Serial No. 39,521. Term of patent 7 years.

To all whom it may concern:

Be it known that I, PHILIP E. MATTHEWS, a citizen of the United States, residing in the city of Plainfield, in the State of New Jersey, have invented a new, original, and ornamental Design for Bus, of which the following is a specification, reference being had to the accompanying drawings, forming a part thereof, which show:

Figure 1 is a front elevation of a bus; and Figure 2 is a perspective view thereof, showing my new design.

I claim:

The ornamental design for a bus, as shown. This specification signed this 23 day of March, A. D. 1931.

PHILIP E. MATTHEWS.
